UNITED STATES PATENT OFFICE.

WESTON M. FULTON, OF KNOXVILLE, TENNESSEE, ASSIGNOR TO THE FULTON COMPANY, OF KNOXVILLE, TENNESSEE, A CORPORATION OF MAINE.

AUTOMOBILE-HEATING SYSTEM.

1,358,838.

Specification of Letters Patent. Patented Nov. 16, 1920.

Application filed August 31, 1916. Serial No. 117,875.

To all whom it may concern:

Be it known that I, WESTON M. FULTON, a citizen of the United States of America, and a resident of Knoxville, Tennessee, have invented a new and useful Improvement 5 in Automobile-Heating Systems, which invention is fully set forth in the following specification.

This invention relates to a heating system 10 for vehicles, and is especially useful when applied as a heating system for automobiles.

An object of this invention is to provide a heating system that utilizes the exhaust 15 gases of the engine as a heating medium, and to regulate the heating effect of such medium by thermosensitive means.

A further object of this invention is to provide a heating system wherein the heating 20 effect of the heating medium is reduced by the admission of air to the system, and also to regulate such admission preferably by thermosensitive means.

Yet another object of this invention is 25 to provide an improved thermosensitive control for a heating system of the type referred to wherein the thermosensitive means may also be adjusted to predetermine the temperature at which the said thermosensitive means assumes control of the means 30 regulating the heating effect of the heating medium.

Other objects relate to the provision of a heating system for automobiles which is 35 simple in construction, inexpensive to manufacture, easy to install, and efficient in operation.

Stated briefly, the invention when applied to the use of exhaust gases as a heating 40 medium comprises, in combination with a radiator and a conduit for conducting the exhaust gases of the engine from the main exhaust conduit to said radiator, means for regulating the heating effect of such gases, 45 preferably comprising an air-intake for the admission of varying quantities of air to the aforesaid conduit to reduce the temperature of said exhaust gases, and means controlling the admission of said air, prefer- 50 ably thermosensitively controlled and shown as subjected to the temperature of the mixture of gases and air in said conduit.

The invention is capable of receiving a variety of mechanical expressions, one of 55 which, for the purpose of illustration, has

been shown on the accompanying drawing, but it is to be expressly understood that the drawing is for purposes of illustration only and is not to be construed as a definition of the limits of the invention, reference being 60 had to the appended claims for that purpose.

The drawing represents somewhat dia- 65 grammatically an elevation of a heating sys- tem embodying the present invention, cer- tain parts being shown in section.

Referring in detail to the drawing, 1 re- 70 presents the main exhaust conduit for con- ducting the exhaust gases of the engine to any preferred form of muffler. In the form 75 shown, a by-pass is provided for the ex- haust gases, as by a coupling 2, and con- ducts 3 and 4, a radiator 5 being provided in said by-pass and a conduit 6 communi- 80 cating with said radiator for conveying the 75 gases to another radiator or radiators or for returning said gases to the main con- duct or the muffler. The radiator 5 may be of any suitable form and positioned in any preferred part of the automobile, the 85 illustrated embodiment comprising a foot- warmer, but such being shown as a matter of convenience only and to be construed as typical of any radiator in any desired position in the automobile.

Means are provided for regulating the 85 heating effect of the exhaust gases, such means, in accordance with the preferred em- bodiment of the invention, comprising 90 means for admitting more or less air to the heating system to reduce the temperature of the exhaust gases when they rise in tem- perature above a predetermined degree. In the form shown, the conduit 3 is provided 95 at the end thereof with a nozzle 7 which delivers into the conduit 4. The latter con- duct is enlarged, as shown at 8, where it surrounds the nozzle 7 and is provided with a lateral tubular extension 9 to constitute 100 an air-intake. The enlarged section 8, with its extension 9, may be connected with the nozzle 7 in any suitable way as by the screw- threaded connection illustrated at 10, and such enlarged section 8 may be connected 105 with the main portion of the conduit 4 by a second screw-threaded connection as illus- trated at 11. The nozzle may also be connect- ed with the conduit 3 by a screw-threaded con- nection as illustrated at 12. The air-intake 110 is preferably provided with a flaring mouth

facing the normal direction of movement of the automobile, as illustrated at 13.

To regulate the admission of air to the said air-intake, a valve member 14 is provided for controlling the inlet end of said extension 9, said valve being operable by a lever 15.

Thermosensitive means are preferably provided for controlling the lever 15 to regulate the admission of air to the gas-conveying conduit, and such thermosensitive means is preferably controlled by the temperature of the gases flowing through said conduit. In the form shown, conduit 4 is embraced by a container 16 charged with a volatile thermosensitive fluid. The container 16 may be lagged with any suitable heat-insulating material, as illustrated at 17, and the lagging incased by a housing 18. Positioned upon the side of the housing 18, and in communication with the container 16, is an expandible and collapsible corrugated metal vessel 19 having a movable end wall 20 carrying an operating member 21 bearing upon the lever 15. Said lever 15 is shown as pivoted on a bracket 22 extending from the housing 18, and the operating member 21 as shown has a pin and socket engagement with such lever. The expandible and collapsible vessel 19 may, if desired, be provided with an inclosing casing, as illustrated at 23.

Means are preferably provided for predetermining the initial temperature at which the thermosensitive means assumes control of the valve member 14, thereby to predetermine the minimum temperature at which said valve begins to open to admit air to the conduit. While any suitable means may be employed to this end, in the form shown movement of the lever 15 by the operating member 21 is opposed by a coiled spring 24 connected at one end to the housing 18 and carrying at its opposite end a block 25 in screw-threaded engagement with an adjusting screw 26 carried by the lever 15. The block 25 may desirably be provided with a pointer 27 to coöperate with a scale 28 for indicating the adjustment of the spring. To control admission of the exhaust gases to the conduit leading to the radiator, a hand-operated valve 29 is shown as provided in the inlet portion of such conduit.

The valve 29 being open to admit the exhaust gases to the conduit 3, such gases rush through the nozzle 7 into the conduit 4 from which they flow through the radiator 5 and out through the conduit 6. If valve 14 be open so that air may flow through the flaring mouth 13 into the extension 9 and the enlarged portion 8 surrounding the nozzle 7, these parts operate after the fashion of an aspirator, whereby air is drawn into the conduit and mixed with the exhaust gases, decreasing the resultant

temperature of the gases flowing through the conduit. So long as the exhaust gases are at a temperature below that predetermined as the proper temperature for the heating of the automobile, valve 14 remains closed. An increase of the temperature of the gases in the conduit 4 tends to volatilize the fluid in the container 16 and to create a pressure which is transmitted to the moveable end wall 20 of the vessel 19; but spring 24 will oppose and prevent movement of such end wall through its action upon the lever 15 until the pressure within the container 16 is sufficient to overcome the tension of the spring. Thereafter the valve 14 will open or close in response to variations of temperature in the conduit 4, maintaining the temperature of the gases flowing through this conduit substantially uniform. The temperature at which valve 14 will begin to open may be varied by adjustment of the spring 24, as above indicated.

While the illustrated embodiment has been described with considerable particularity, it is to be expressly understood that the invention is not to be restricted to the form shown as it is capable of receiving a variety of mechanical expressions, some of which will readily suggest themselves to those skilled in the art. Furthermore, certain features of the invention are capable of use without other features thereof; therefore, the limits of the invention are to be determined by reference to the claims hereinafter appended.

What is claimed is:—

1. A heating system for automobiles comprising a radiator, a conduit for conducting the exhaust gases of the engine to said radiator, an air-intake communicating with said conduit for admitting air to said conduit to reduce the temperature of the gases flowing therethrough, and means for controlling said intake.

2. A heating system for automobiles comprising a radiator, a conduit for conducting the exhaust gases of the engine to said radiator, an air-intake communicating with said conduit for admitting air to said conduit to reduce the temperature of the gases flowing therethrough, and thermosensitive means for controlling said intake.

3. A heating system for automobiles comprising a radiator, a conduit for conducting the exhaust gases of the engine to said radiator, an air-intake communicating with said conduit for admitting air to said conduit to reduce the temperature of the gases flowing therethrough, and means controlled by the temperature of the gases flowing through said conduit for controlling said intake.

4. A heating system for vehicles comprising a radiator, a conduit for conveying a heating fluid to said radiator, an air-intake communicating with said conduit for ad-

mitting air to said conduit to reduce the temperature of the fluid flowing therethrough, and means for controlling said intake.

named conduit for admitting air to said conduit to reduce the temperature of the gases flowing therethrough, and a valve regulating the passage of air through said air-intake. 65

5 5. A heating system for vehicles comprising a radiator, a conduit for conveying a heating fluid to said radiator, an air-intake communicating with said conduit for admitting air to said conduit to reduce the 10 temperature of the fluid flowing therethrough, and thermosensitive means for controlling said intake.

11. A heating system for automobiles comprising a radiator, a conduit for the exhaust gases of the engine provided with a nozzle, a conduit for conducting said gases to said radiator and into which said nozzle delivers, an air-intake provided with a flaring mouth and communicating with said last-named conduit for admitting air to said conduit to reduce the temperature of the gases flowing therethrough, a valve regulating the passage of air through said air-intake, and theremosensitive means controlling said valve. 11

6. A heating system for vehicles comprising a radiator, a conduit for conveying a heating fluid to said radiator, an air-intake 15 communicating with said conduit for admitting air to said conduit to reduce the temperature of the fluid flowing therethrough, and means controlled by the temperature 20 of the fluid flowing through said conduit for controlling said intake.

12. A heating system for automobiles comprising a radiator, a conduit for conducting the exhaust gases of the engine to said radiator, means for regulating the heating effect of said exhaust gases, and thermosensitive means for controlling said last-named means. 85

7. A heating system for automobiles comprising a radiator, a conduit for the exhaust gases of the engine provided with a nozzle,
25 a conduit for conducting said gases to said radiator and into which said nozzle delivers, an air-intake communicating with said last-named conduit for admitting air to said conduit to reduce the temperature of the
30 gases flowing therethrough, and a valve regulating the passage of air through said air-intake.

13. A heating system for automobiles 90 comprising a radiator, a conduit for conducting the exhaust gases of the engine to said radiator, means for regulating the heating effect of said exhaust gases, and means controlled by the temperature of the gases 95 flowing through said conduit for controlling said last-named means.

35 8. A heating system for automobiles comprising a radiator, a conduit for the exhaust gases of the engine provided with a nozzle, a conduit for conducting said gases to said radiator and into which said nozzle delivers, an air-intake communicating with said last-named conduit for admitting air to said conduit to reduce the temperature of the gases flowing therethrough, a valve regulating the passage of air through said air-intake, and thermosensitive means controlling said valve.

14. A heating system for automobiles comprising a radiator, a conduit for conducting the exhaust gases of the engine to said radiator, a valve regulating the admission of air to said conduit to reduce the temperature of the air flowing therethrough, thermosensitive means controlling said valve, and means for predetermining the temperature at which said thermosensitive means begins to operate said valve. 100 105

45 9. A heating system for automobiles comprising a radiator, a conduit for the exhaust gases of the engine provided with a nozzle, a conduit for conducting said gases to said radiator and into which said nozzle delivers, an air-intake communicating with said last-named conduit for admitting air to said conduit to reduce the temperature of the gases flowing therethrough, a valve regulating the passage of air through said air-intake, and means controlled by the temperature of the gases flowing through said last-named conduit for controlling said valve.

15. A heating system for automobiles comprising a radiator, a conduit for conducting the exhaust gases of the engine to said radiator, means for regulating the heating effect of said exhaust gases, thermosensitive means controlling said regulating means, and means for predetermineding the temperature at which said thermosensitive means assumes control of said regulating means.

60 10. A heating system for automobiles comprising a radiator, a conduit for the exhaust gases of the engine provided with a nozzle, a conduit for conducting said gases to said radiator and into which said nozzle delivers, an air-intake provided with a flaring mouth and communicating with said last-

16. A heating system for automobiles comprising a radiator, a conduit for conducting the exhaust gases of the engine to said radiator, means for regulating the heating effect of said exhaust gases, thermosensitive means controlling said regulating means, and means for predetermining the temperature at which said thermosensitive means assumes control of said regulating means, said last-named means comprising a spring opposing movement of said

regulating means by said thermosensitive means, and means for adjusting the tension of said spring.

17. A heating system for automobiles comprising a radiator, a conduit for conducting the exhaust gases of the engine to said radiator, means for regulating the heating effect of said exhaust gases, and thermosensitive means controlling said regulating means, said thermosensitive means comprising a container embracing said conduit and charged with a volatile fluid, and an expansible and collapsible vessel in communication with said container, said vessel having a movable end wall responsive to pressure changes in said container and operatively related to said regulating means.

18. A heating system for automobiles comprising a radiator, a conduit for conducting the exhaust gases of the engine to said radiator, an air-intake communicating with said conduit for admitting air to said conduit to reduce the temperature of the air flowing therethrough, a valve controlling the passage of air through said air-intake, and thermosensitive means controlling said valve, said thermosensitive means comprising a container embracing said conduit and charged with a volatile fluid, and an expansible and collapsible vessel in communication with said container, said vessel having a movable end wall responsive to pressure changes in said container and operatively related to said valve.

19. A heating system for automobiles comprising a radiator, a conduit for conducting the exhaust gases of the engine to said radiator, means for controlling admission of said gases to said conduit, means

for controlling admission of air to said conduit to reduce the temperature of the gases flowing therethrough, and thermosensitive means controlling said last-named means.

20. A heating system for automobiles comprising a radiator, a conduit for conducting the exhaust gases of the engine to said radiator, means for controlling admission of said gases to said conduit, means for controlling admission of air to said conduit to reduce the temperature of the gases flowing therethrough, and means controlled by the temperature of the gases flowing through said conduit for controlling said last-named means. 55

21. A heating system for automobiles comprising a radiator, a conduit for conducting the exhaust gases of the engine to said radiator, a valve for controlling the gases in said conduit, and means controlled by the temperature of the gases flowing through said conduit for controlling said valve.

22. A heating system for automobiles comprising a radiator, a conduit for conducting the exhaust gases of the engine to said radiator, an air-intake communicating with said conduit for admitting air to said conduit to reduce the temperature of the gases flowing therethrough, a valve controlling said air-intake, and thermosensitive means subjected to the temperature of the mixture of exhaust gases and air for controlling said valve. 65 70

In testimony whereof I have signed this specification. 75

WESTON M. FULTON.
